UNITED STATES PATENT OFFICE.

NOAH J. BECKNER AND JOHN A. MORRISON, OF NORTH YAKIMA, WASHINGTON,
ASSIGNORS TO SAFETY PATENT CO., A CORPORATION OF WASHINGTON.

SWITCH-LOCK.

1,261,206.

Specification of Letters Patent.

Patented Apr. 2, 1918.

Application filed November 8, 1917. Serial No. 200,963.

To all whom it may concern:

Be it known that we, NOAH J. BECKNER and JOHN A. MORRISON, both native-born citizens of the United States, residing at 5 North Yakima, in the county of Yakima and State of Washington, have invented certain new and useful Improvements in Switch-Locks, of which the following is a specification.

10 This invention has relation to locks for railway switch stands, and has for an object to provide a lock readily attachable to a standard switch stand and adapted to lock the lever in one position thereof, and embodying means for preventing the removal of the key for actuating the lock while the locking mechanism is in an unlocked position.

Another object of the invention is to provide a locking means of the character above described embodying a key actuated locking bolt adapted to retain the key within the lock while the bolt is in an unlocked position, and a releasing means engageable by the switch lever when the switch lever is thrown to an off position to release the key actuating mechanism after the bolt has been returned to locking position so as to permit removal of the key.

30 In addition to the foregoing our invention comprehends improvements in the details of construction and arrangement of the parts to be hereinafter more fully described and particularly set forth in the appended claims.

35 In the accompanying drawings in which similar and corresponding parts are designated by the same characters of reference throughout the several views in which they appear:

40 Figure 1, is a view in front elevation of a portion of a switch stand illustrating the application thereto of our invention.

Fig. 2, is a longitudinal vertical section taken through the casing of our improved lock.

Fig. 3, is a horizontal section taken on the line 3—3 of the preceding figure.

Fig. 4, is a vertical section taken on the line 4—4 of Fig. 2, and

50 Fig. 5, is a similar view taken on the line 5—5 of Fig. 2.

With reference to the drawings, 10 indicates a casing including front and rear walls 11 and 12. The rear wall 12 is formed with

a pair of laterally extending spaced ears 13 55 to engage opposite sides of the upper end of the switch standard indicated at 14, the ears being apertured to receive the bolt 15 provided in said standard to pivotally support the switch lever indicated at 16, the lever 60 being movable from an off or depending position as shown in full lines in Fig. 1, to a horizontal or operative position as shown in dotted lines. The rear end of the lever 16 is formed with a laterally extending lug 17, 65 adapted to enter an opening 18 in the rear wall 12 of the casing when the lever is in an offset position. The upper end of the rear plate 12 is formed with an overhanging lug 19 to engage over the top edge of the switch 70 stand to secure the lock casing thereto. A pair of flanges 20 and 21 are formed adjacent the vertical edges of the opening 18 of the rear wall of the casing and extend inwardly, the flange 20 having an opening through 75 which a horizontal transversely movable locking bolt 22 extends, a pair of spaced guides 23 being provided upon the inner face of the plate 12 of the casing to form a guide and support for the locking bolt. It 80 will be noted that the bolt 22 is capable of movement from a position to extend entirely across the opening 18, to a position within the casing wherein the opening 18 of the casing is left unobstructed. 85

A keyhole 24 is formed in the front plate 11 of the casing adjacent the upper end thereof and adjacent one vertical edge to receive a key 25 which may be of hollow construction whereby a stud 26 forming a ward 90 and secured to the inner face of the plate 12 may enter the recess of the key. A bolt actuating lever indicated at 27 is provided and is mounted for rotation about a pivot 28, one end of the lever having an elongated opening 29 through which a pin 30 secured to the locking bolt 22 extends whereby the locking bolt may be shifted by actuation of the lever. The opposite or upper end of the lever is bifurcated to form opposed members 31 and 32 between which the keys operate. The inner surface of the bifurcated portion is curved and is engageable by the bit 33 of the key whereby the lever may be oscillated in one direction or the other as the key is 100 rotated. The terminal of the member 32 of the bifurcated portion is formed with a lateral extending lug 34 engageable by the 105

bit of the key to prevent further rotation of the key when the same is rotated in a direction to unlock the bolt.

A mechanism for retaining the bolt 22 in an unlocked position is provided consisting of a lever 35 located in the lower portion of the casing and pivotally mounted upon a stud 36, and having an elongated opening 37 in its upper end to receive the pin 30 of the locking bolt, the lever also having a lug 38 at its opposite end for engagement with the hooked shaped end 39 of a latch lever 40 pivoted as at 41. When the lug 38 is engaged behind the hook-shaped end 39 of said lever 40 the bolt 22 will be held in an unlocked position precluding the return of the bolt to a locked position until the lug 38 is released.

The releasing mechanism comprises a lever 42 mounted upon ears 43 formed by bending the material of the flange 21 which is located adjacent the opening 18 of the casing, one end of the lever 42 extending within the casing and the other extending 25 across the opening 18 in a position to be engaged and actuated by the lug 17 of the switch lever 16 when said lever is moved to a depending or off position. The inner end of the lever 42 is formed with a depending extension 44 which is pivotally connected to a link 45 at one end thereof, the other end of the link being pivotally connected to the latch lever 40 as clearly shown in Fig. 3. A leaf spring 46 is secured at one end to a lug 47 extending inwardly from the rear face of the rear plate 12 of the casing while the opposite end engages the inner end of the lever 42 to retain the parts of the releasing mechanism in a manner to insure engagement of the lock 38 of the bolt retaining mechanism when said bolt is moved to an unlocked position.

In operation, to lock the switch lever the same is moved to a depending position 45 whereby the laterally extending lug 17 at the upper end is inserted in the opening 18 in the rear of the casing and engaged against the lever 42, rocking said lever whereby to rock latch lever 40 and to disengage the hook end 39 thereof from the lug 38 whereby when the key is inserted in the lock and rotated counter-clockwise, the bit 33 will engage the member 31 of the lever 27 and move the locking bolt 22 to a closed position, the 50 bolt entering the aperture in the end of the lug 17 of the switch lever thereby preventing movement of said switch lever to an operative position. The locking bolt 22 may be released by rotating the key in a reverse direction. It will be noted however, that when the key is thus rotated to reverse position, the bit of the key is positioned with relation to the key hole in a manner to prevent removal of the key and at the same time 55 upon a movement of the switch lever to re-

move the lug 17 thereof from within the casing the spring 46 by engagement with the lever 42 to which the lever 40 is connected will urge the latch lever 40 in a position to engage the lug 38 whereby the locking bolt 22 will be held in an unlocked position and prevent the removal of the key inasmuch as the key must be returned to a position to bring its bit 33 in alinement with the key hole which movement of the key is precluded by engagement with the member 31 of the lever 27. It will be apparent therefore, that the key cannot be removed from the lock until the switch lever 16 is returned to an off or depending position whereby the lug 17 may engage the lever 42 to release the bolt retaining mechanism. A safety device is thus provided which will insure the return of the switch lever to an off position each time, the difficulty in removing the key from the lock notifying the switch operator that the switch lever has not been properly positioned.

While we have illustrated and described our invention with some degree of particularity, we realize that in practice various alterations thereover may be made, and we therefore desire to reserve the right and privilege of changing the form of the details of construction, or otherwise altering the arrangement of the correlative parts without departing from the spirit of the invention or the scope of the appended claims.

Having thus described our invention, what we claim as new and desire to secure by Letters Patent is:—

1. A lock for switch stands, including a casing having an opening therein, a bolt slidably mounted to extend across the opening and to enter the aperture of one end of a switch lever, a lever pivoted within the casing having one end pivotally connected to the bolt, the other end being bifurcated to receive a key therebetween whereby the lever may be oscillated, means for retaining the bolt in an unlocked position, and means forming an obstruction across the opening of the lock casing and engageable by the end of the switch lever to release said retaining means to permit the bolt to be shifted to closed position.

2. A lock for switch stands including a casing having an opening therein, a bolt slidably mounted to extend across the opening and to enter the aperture of one end of a switch lever, key operated means for shifting the bolt, a lever pivotally mounted and having one end pivotally connected to the bolt to be actuated thereby, a lug on the opposite end of the lever, a latch lever having a hooked terminal to engage the lug of the first mentioned lever, and a lever pivotally mounted having one end extending across the opening of the lock casing to form an obstruction therefor, engageable by the end

of the lever to rock said latch member to release the lever whereby the locking bolt may be moved to locked position.

3. A lock for switch stands, including a casing having an opening therein, a bolt slidably mounted to extend across the opening and to enter the aperture of one end of a switch lever, a lever operatively connected to the bolt to shift the same, a pair of spaced members formed on the lever to receive the bit of a key therebetween whereby to move the lever by engagement of the bit with either member, an inwardly extending lug on one member engageable by the bit to prevent movement of the key in one direction, a

lever shiftable by movement of the bolt, means engaging said lever when the bolt is in an unlocked position to retain the same therein, and means forming an obstruction across the opening of the lock casing engageable by the end of the switch lever to release said remaining means to permit the bolt to be moved to closed position. 20

In testimony whereof we affix our signatures in presence of two witnesses.
